CLAIM

The ornamental design for an organizer system and wall mount for the organizer system, as shown and described.

DESCRIPTION

FIG. 1 is a top right front perspective view of a design for an organizer;

FIG. 2 is a top view of the organizer of FIG. 1;

FIG. 3 is a bottom view of the organizer of FIGS. 1-2;

FIG. 4 is a left side view of the organizer of FIGS. 1-3;

FIG. 5 is a right side view of the organizer of FIGS. 1-4;

FIG. 6 is a front view of the organizer of FIGS. 1-5; and

FIG. 7 is a rear view of the organizer of FIGS. 1-6.

The dashed lines immediately adjacent to the shaded areas in the figures represent the boundaries of the claimed design. The dashed lines in the figures illustrate the portions of the design that form no part of the claimed design. None of the broken lines form any part of the claimed design.
